(57) **CLAIM**

The ornamental design for a baseball bat, as shown.

DESCRIPTION

FIG. 1 is a perspective view of the design for the baseball bat;

FIG. 2 is an elevation view thereof; and,

FIG. 3 is a bottom view thereof.

The broken lines shown in the figures are for illustrative purposes only and form no part of the claimed design.

1 Claim, 3 Drawing Sheets

FIG. 1

FIG. 2

FIG. 3
